The ornamental design for a desk, as shown and described.

DESCRIPTION

FIG. 1 is a perspective view of a desk showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the desk in a folded configuration;

FIG. 9 is a front view thereof; and,

FIG. 10 is a bottom view thereof.

The broken lines in FIGS. 1-10 are for the purpose of illustrating portions of the desk that form no part of the claimed design.
